UNITED STATES PATENT OFFICE.

CHARLES F. BLACK, OF DAYTON, OHIO.

ELECTRIC SWITCH.

No. 825,632.

Specification of Letters Patent.

Patented July 10, 1906.

Application filed July 28, 1905. Serial No. 271,673.

To all whom it may concern:

Be it known that I, CHARLES F. BLACK, a citizen of the United States, residing at Dayton, in the county of Montgomery and State 5 of Ohio, have invented a new and useful Electric Switch, of which the following is a specification.

This invention relates to electric switches, and has for its principal object to provide a 10 novel form of switch of that general type in which alternate depressions of the push-button or similar switch-operating member will make and break a circuit.

A further object of the invention is to provide a switch in which a revoluble contact-breaker is provided with a plurality of equidistantly-spaced radial arms formed of insulating material and movable between a pair of normally engaged spring circuit-closers, 20 said contact-breaker being connected to an operating mechanism which at each second operation moves one of the arms between the circuit-closers for the purpose of breaking the circuit.

With these and other objects in view, as will more fully hereinafter appear, the invention consists in certain novel features of construction and arrangement of parts herein-after fully described, illustrated in the accompanying drawings, and particularly pointed out in the appended claim, it being understood that various changes in the form, proportions, size, and minor details of the structure may be made without departing from 35 the spirit or sacrificing any of the advantages of the invention.

In the accompanying drawings, Figure 1 is a sectional elevation of a switch constructed in accordance with the invention. Fig. 2 is a 40 transverse section of the same on the line 2 of Fig. 1. Fig. 3 is a detail edge view of the circuit-breaker. Fig. 4 is a similar view with the parts in a different position.

Similar numerals of reference are employed 45 to indicate corresponding parts throughout the several figures of the drawings.

The working parts of the switch are mounted on a suitable base 10, which may be formed of insulating material, and secured to the 50 base are two small blocks 11, each carrying a spring 12, forming a terminal of the circuit. The current-conducting wires 14 are connected to the springs 12 by suitable screws 15, which also serve to hold the springs to the blocks 11, and the free ends of the springs are oppositely curved and are normally held in

contact with each other in order to complete the circuit.

Secured to the base is a pair of standards 16, which may be formed of sheet metal, and from the top of these standards extends a plate 17, that is provided with a guiding-opening for the passage of a push-rod 18. At the outer end of the rod is a push-button 19, that extends through a suitable opening 20, formed in a semispherical casing 21, and outward movement of the button is limited by a flange 22, formed at the inner end of said button and against the inner face of said flange bears one end of a spring 23, the opposite end of which bears against the plate 17. The two standards 16 are provided with suitable bearings for a shaft 25, carrying a ratchet-wheel 26, which in the present instance is provided with eight teeth, and these 75 teeth are engaged by a pawl 27, pivotally mounted on the push-rod 18 and held in operative position by a spring 28.

Secured to the shaft 25 is a circuit-breaker 30, that preferably is formed of insulating material. This circuit-breaker includes a centrally-disposed hub 31 and a plurality of arms 32, four of such arms being shown in the present instance. The opposite edges of each arm are tapered to form a relatively 85 thin entering edge, and the central portion of each blade is provided on each face with a recess 33, that is curved in cross-section, the recesses being adapted to receive the curved ends of the springs, and from their peculiar 90 shape said arms are held by the springs in circuit-breaking position until inward pressure on the button 19 forces the pawl 27 into engagement with the ratchet-wheel and rotates the latter to the extent of a single tooth. 95

The switch is of such construction that with one of the circuit-breaking arms normally between the contact-spring and the circuit-breaker an inward movement of the push-button 19 will rotate the ratchet-wheel 100 or shaft 25 and the circuit-breaker until the arm is moved from between the spring, allowing the latter to move into contact, and thus close the circuit. The circuit will remain closed until on the next movement of 105 the push-button the ratchet-wheel is rotated one-eighth of a revolution and another circuit-breaking arm is forced between the contacts.

Having thus described the invention, what 110 is claimed is—

The combination in an electric switch, of

a pair of spring-contacts forming the terminals of an electric circuit and having curved contact-faces, a shaft, a revoluble circuit-breaker carried by the shaft and having a plurality of equidistantly-arranged radial arms, said arms having tapered edge portions, and being provided with recessed faces which when in engagement with the curved contact-faces hold the circuit-breaker in position, a ratchet-wheel secured to the shaft, a

push-rod, and a pawl carried by the rod and engaging the teeth of the ratchet-wheel.

In testimony that I claim the foregoing as my own I have hereto affixed my signature in the presence of two witnesses.

CHARLES F. BLACK.
